UNITED STATES PATENT OFFICE

ALBERT J. ALLISON, OF DAYTON, OHIO, ASSIGNOR TO SIMONDS WORDEN WHITE COMPANY, OF DAYTON, OHIO, A CORPORATION OF OHIO

BEATER ROLL CONSTRUCTION

Application filed December 3, 1928. Serial No. 323,234.

This invention relates to the construction of rolls for beating engines used in beating paper stock, and in some particulars it is an improvement on the construction disclosed in my application Serial No. 248,500. Inasmuch as the present roll is of the same general type as that of said application, and as the objects, principles and operation of the type are set forth in said application, I shall proceed to describe the present construction, referring during the description to the accompanying drawings, in which

Fig. 1 is a longitudinal section through a portion of a roll embodying my present improvements;

Fig. 2 is a view of a portion of the exterior of the roll. In this view the fact that we are looking at a cylindrical object is ignored and the parts are drawn as they would appear if the outer part of the roll were flattened out;

Fig. 3 is a section of the roll taken on line 3-3 of Fig. 1, and

Fig. 4 is an end view of one of the channels which contain the fly bars, when the channel is but partly formed.

Referring now to Fig. 1 the roll comprises two circular members 10, and an intermediate circular member 11, mounted on a shaft 12. In the art these members are commonly called "heads", so I shall employ that term hereinafter. The three heads are secured to the shaft in some suitable way (not shown), so that they are in effect integral with the shaft. Each head has a series of wide recesses formed in its periphery, as is indicated at 13, Fig. 3. The walls of these recesses lean toward each other, or, as will hereinafter be said, the walls converge. The heads are so arranged on the shaft that the recesses in the several heads are in alignment. Into each row of recesses I insert a channel 14. These channels are formed with converging walls, and they are slidden endwise into their respective rows of recesses. In order to insure their being tight in the recesses, I make the channels slightly wider at one end than at the other. In other words, the channels taper slightly. The recesses in the several

heads are graduated in width to correspond to the taper of the channels, and the parts are so proportioned that the channel must be driven into the heads the last two or three inches. I have not attempted to illustrate this taper of the channels, because it is so slight that it could not be seen unless very much exaggerated, which would be misleading. Each head 10 is rabbeted at its periphery to receive a series of segmental plates 15, which plates are secured to the heads by cap screws 16. These segments cover the ends of the channels and their purpose will be described presently.

The fly bars, 20, stand on edge in the channels 14. These bars are mere sheets of metal, corrugated. Between the fly bars are spacing members 21. The ends of the bars and of the spacing members which abut the walls of the channels are made angular, to conform to the angularity of the walls of the channels. By this means the fly bars and spacing members are secured in the channels dove-tail fashion. In effect they are interlocked with the walls of the channels. The purpose of the segmental plates 15 is to press the fly bars and the spacing members endwise into the channels. In order to insure the segments bearing against the bars and spacers instead of against the ends of the channels, the channels are made slightly short. If desired the cap screws underneath the channels may be replaced by rods which pass lengthwise through the roll, with nuts screwed on each end in recesses provided in the plates for the cap screw heads. These rods should pass through clearance holes in the head 11. This will be readily understood by any mechanic, so it is unnecessary to illustrate this modification.

The spaces between the channels are filled with wood, as is shown in Fig. 2, where one space is entirely filled with wood. Referring to Fig. 3, the construction of this wood filling is plainly seen. It consists of a strip of wood 25 lying against each channel, with a key strip 26 driven between the two strips 25. In order to prevent the strips 25 from slipping out, each strip has a flange 27 which extends under the chan-

nel. The angularity of the key strip 26 is made so small that it cannot slip with reference to the strips 25. These fillers are put into the roll while the wood is dry. When the roll is put in service the wood 5 becomes thoroughly soaked with water and swells; the pressure against the sides of the channels then becomes very great, so great that it tends to press the walls of the channels, particularly the outer portions, 10 against the fly bars and spacing members in the channel and clamps the latter tightly between the walls. To facilitate this the bottoms of the channels may be slotted. 15 This is illustrated in Fig. 2 of the drawings, where it will be seen that slots 30 extend from a point near the end of the channel 14 to a point near the middle of the channel. These slots are formed in the bottom 20 of the channel, paralleling and close to the channel wall, and, as will be seen in Fig. 2, they extend at each end considerably past the zone which is subject to the pressure of the wood fillers. The remaining attachments 25 between the walls and bottom being comparatively narrow the walls are more readily pressed against the bars and spacers in the channel, it being understood that the bars and spacers are carefully fitted in the 30 channel, so there need be but slight movement of the walls. If desired additional narrow necks connecting the walls to the bottom of the channel may be left midway between the heads, in order to give the bottoms 35 of the channels more support. This is such an obvious modification that I deem it unnecessary to illustrate it. Thus the channel walls which sustain the pressure of the wood fillers, are adapted to yield under the pressure and clamp the bars and spacing members very tightly between the walls. 40 For the purpose of protecting the bottoms of the channels, especially in case rather hard metal is used in making the fly bars, I may lay in the bottom of each channel a thin plate 31, composed of metal which is more durable than the metal composing the channel itself.

At the ends of the roll I prefer to have the fly bars extend endwise to the outer surfaces of the segments 15. Of necessity this extension is free standing and in order to reinforce these overhanging portions, I tie them together as at 32. In fact, I simply make two fly bars with one piece of metal, as is quite clearly illustrated in Fig. 2.

The channels may be made of cast iron, malleable iron or cast steel. I prefer, however, to roll them, starting with a billet, in the way rolled sections are usually made. Obviously, a channel with converging walls cannot be rolled in the ordinary way. To overcome this difficulty, I roll the bottom of the channel to a curved form, and then

by a separate operation I flatten the bottom. The form in which the channel is rolled is illustrated in Fig. 4. In this figure a dotted line is drawn across the bottom of the channel a short distance from each wall. Preferably, I form the portions of the bottom between these dotted lines and the wall flat, and make the wall the proper angle with reference to these flat portions of the bottom. Then the only portion of the bottom which needs to be straightened is that lying between the two dotted lines. These channels are rolled in long lengths, and then cut to the length required for use in the rolls. Flattening the bottom 70 of the channels is deferred until after the channels are cut to length. Then the flattening can be done in various ways, all of which are so simple and well understood by persons skilled in the art, that I deem it unnecessary to illustrate or describe any apparatus for doing it.

While I have described the preferred construction, it is not to be understood that the practice of my invention is limited to the specific construction shown. For example, I do not limit myself to the use of corrugated fly bars, for my construction would be equally useful should straight fly bars be used. In the drawings I have shown the fly bars in successive groups leaning in opposite directions; if desired, the bars may lean in the same direction in all groups, or as is suggested in my application above mentioned, there may be more groups leaning 90 in one direction than in the other. While I prefer securing the channels in the recesses dove-tail fashion, some other form of interlock, for example, that which I have shown in my application previously mentioned, might be substituted. Having illustrated and described my invention, I claim:

1. In a beater roll, a series of heads secured on a shaft, said heads having broad recesses in their peripheries, channels connecting the heads and secured in said recesses with their flanges extending outward, fly bars standing on edge in said channels, alternating with spacing members, and plates secured to the outside heads, said plates closing the ends of the channels and being adapted to clamp the fly bars and spacing members endwise therein.

2. In a beater roll, a series of heads secured on a shaft, said heads having broad recesses in their peripheries, which recesses have converging walls, channels connecting the heads and lying in said recesses, which channels have converging walls, thereby securing them in the recesses dove-tail fashion, fly bars standing on edge in said channels and alternating with spacing members, and plates secured to the outside heads, whereby the ends of the channels are closed 120 125 130

and the fly bars and the spacing members are clamped endwise.

3. In a beater roll, a series of heads secured on a shaft, said heads having broad recesses in their peripheries, which recesses have converging walls, channels connecting the heads and lying in said recesses, which channels have converging walls, thereby securing them in the recesses dove-tail fashion,

5 said channels being slightly tapered longitudinally and the recesses graduated in width, so the channels can be made tight in the recesses by driving them endwise, fly bars standing on edge in said channels and 10 alternating with spacing members, and plates secured to the outside heads, whereby the ends of the channels are closed and the fly bars and the spacing members are clamped endwise.

20 4. In a beater roll, a series of heads secured to a shaft, said heads having broad recesses in their peripheries, channels connecting the heads and secured in said recesses with their flanges extending outward, 25 fly bars secured in said channels, and strips of wood driven between the walls of adjacent channels.

5. In a beater roll, a series of heads secured to a shaft, said heads having broad recesses in their peripheries, with converging walls, channels connecting the heads and lying in said recesses, which channels have converging walls, thereby securing them in the recesses dove-tail fashion, fly bars secured in said channels, and strips of wood driven between the walls of adjacent channels.

6. In a beater roll, a series of heads secured to a shaft, said heads having broad recesses in their peripheries, with converging walls, channels connecting the heads and lying in said recesses, which channels have converging walls, thereby securing them in the recesses dove-tail fashion, fly bars secured in said channels, and strips of wood driven between the walls of adjacent channels, the bottom of the channels having slots parallel and close to each wall, said slots being of such extent that the union of each 50 wall to the bottom is reduced to a few narrow necks, thereby adapting the walls to yield laterally under the pressure imparted by the wood fillers and tightly clamp the contents of the channel between the walls, 55 there being a neck at each head.

7. In a beater roll, a series of heads secured to a shaft, said heads having broad recesses in their peripheries, with converging walls, channels connecting the heads and lying in said recesses, the channels having converging walls, thereby securing themselves in the recess dove-tail fashion, fly bars secured in the channels, and wooden fillers closing the spaces between adjacent channels, said fillers comprising strips

which lie against the channel walls, each strip having a flange extending under the edge of the wall, and a key strip driven between said strips.

8. In a beater roll, a series of heads secured on a shaft, said heads having broad recesses in their peripheries, with converging walls, channels connecting the heads and lying in said recesses, the walls of the channels also converging, thus securing the 70 channels in the recesses dove-tail fashion; fly bars in each channel, comprising plates of metal standing on edge and extending obliquely across the channel, spacing members between said bars, the ends of said 75 bars and members being angular to conform to the inclination of the channel walls, plates outside of the terminal heads, contiguous to the ends of the channels and adapted to bear against the fly bars and spacers, 80 and means for drawing said plates in, thereby clamping the bars and spacing members endwise.

9. In a beater roll, a series of heads secured on a shaft, said heads having broad 90 recesses in their peripheries, with converging walls, channels connecting the heads and lying in said recesses, the walls of the channels also converging, thus securing the 95 channels in the recesses dove-tail fashion; fly bars in each channel, comprising corrugated plates of metal standing on edge and extending obliquely across the channel, spacing members between said bars, the ends of said 100 bars and members being angular to conform to the inclination of the channel walls, plates secured to the outside heads and bearing against the contiguous bars and spacing members, whereby said bars and members are clamped endwise in the channel, 105 and strips of wood driven between the walls of adjacent channels.

10. In a beater roll, a series of heads secured on a shaft, said heads having broad recesses in their peripheries, with converging walls, channels connecting the heads and lying in said recesses, the walls of the channels also converging, thus securing the 110 channels in the recesses dove-tail fashion; fly bars in each channel, comprising plates of metal standing on edge and extending obliquely across the channel, spacing members between said bars, the ends of said 115 bars and members being angular to conform to the inclination of the channel walls, plates outside of the terminal heads, contiguous to the ends of the channels and adapted to bear against the fly bars and spacers, means for drawing said plates in, thereby clamping the bars and spacing 120 members endwise and strips of wood driven between the walls of adjacent channels.

11. In a beater roll, a series of heads secured on a shaft, said heads having broad recesses in their peripheries, with converging 125

- ing walls, channels connecting the heads and lying in said recesses, the walls of the channels also converging, thus securing the channels in the recesses dove-tail fashion; 5 fly bars in each channel, comprising plates of metal standing on edge and extending obliquely across the channel, spacing members between said bars, the ends of said bars and members being angular to conform to the inclination of the channel walls, plates outside of the terminal heads, contiguous to the ends of the channels and adapted to bear against the fly bars and spacers, means for drawing said plates in, 10 thereby clamping the bars and spacing members endwise and strips of wood driven between the walls of adjacent channels, the bottoms of the channels having slots paralleling and close to each wall, extending from head to head, whereby the channel walls are adapted to yield under the pressure of said wood filling when it gets wet, thereby clamping the fly bars and spacing members tightly between the channel walls. 15
- 20 12. In a beater roll, a series of heads mounted on a shaft, said heads having broad recesses in their peripheries, channels lying in said recesses with their walls extending outward, and bridging the spaces between the heads, means for holding the channels in the recesses in opposition to centrifugal or other forces tending to dislodge them, fly bars standing on edge in each channel, alternating with spacing members, means for holding said bars and spacing members in the channels in opposition to centrifugal or other forces tending to dislodge them, plates at each end of the channel, and means for drawing said plates 25 toward each other to clamp the bars and spacing members endwise. 30
- 35 13. In a beater roll, a series of heads mounted on a shaft, said heads having broad recesses in their peripheries, channels lying in said recesses with their walls extending outward, and bridging the spaces between the heads, means for holding the channels in the recesses in opposition to centrifugal or other forces tending to dislodge them, fly bars standing on edge in each channel, alternating with spacing members, means for holding said bars and spacing members in the channels in opposition to centrifugal or other forces tending to dislodge them, plates at each end of the channels, means for drawing said plates 40 toward each other to clamp the bars and spacers endwise, and wood fillers driven between the channels. 45
- 50 14. A beater roll comprising beater bars arranged in groups, each group being secured in a container having a bottom and sides, a super-bottom in said container comprising a relatively thin plate composed of metal having durability superior to the ma-

terial composing said container, on which plate the beater bars rest.

55 15. In a beater roll, a series of heads mounted on a shaft, said heads having recesses in their peripheries, channels lying in said recesses with their walls extending outward, and interlocked with the heads to prevent radial displacement, fly bars in said channels, wood fillers driven between the walls of adjacent channels, the bottoms of the channels having slots paralleling and close to each wall, said slots extending beyond the ends of said wood fillers, whereby the walls of the channels are adapted to yield under the pressure of the wood and be 60 pressed against the fly bars to hold them immovable in the channels. 70

65 16. In a beater roll, a channel for holding the fly bars, the bottom of said channel having slots close to and paralleling the sides of the channel, said slots being of such extent that the union of each wall to the bottom is reduced to a few narrow necks. 75

70 17. In a beater roll, a forged channel for holding fly bars, the walls of said channel forming an acute angle with the bottom, the bottom having slots close to and paralleling the sides, said slots being of such extent that the union of each wall to the bottom is reduced to a few narrow necks. 80

75 18. In a beater roll, a removable forged channel for holding the fly bars, the walls thereof forming acute angles with the bottom, thus causing the walls to converge. 90
